HYDRAULIC TOOL FLUID RESERVOIR

Marvin Lee, Rye, N. Y., assignor to Burndy Engineering Company, Inc., a corporation of New York

Application July 31, 1940, Serial No. 349,028

3 Claims. (Cl. 220—63)

This invention relates to fluid reservoirs for use on hydraulically actuated mechanisms of the type illustrated in application filed August 13, 1938, Ser. No. 224,820 for a Portable hydraulic press, by Irving Frederick Matthysse.

Ordinarily a hydraulic tool which must be operated in any position is equipped with a cylindrical fluid reservoir in which a follow-up piston fits snugly. This piston has packing placed about its diameter in order to seal it in the cylindrical reservoir. The fit of the packing must be snug enough to prevent fluid or air leakage past the piston but at the same time, the piston must be able to move freely. As the fluid is pumped from the reservoir into the pressure chamber, atmospheric pressure forces the piston into the reservoir, taking up the space of the displaced oil. As a practical matter, however, atmospheric pressure is usually insufficient to overcome the friction of the packing against the cylinder walls and a follow-up spring is necessary to assist in moving the follow-up piston forward. The action of this spring is to apply a constant force against the follow-up piston which in turn applies pressure against the hydraulic fluid even when the tool is not operating. As a consequence of constant pressure on the fluid, some of the fluid is forced past the piston packing in a slow leakage. This leakage is insignificant for short periods of time but for extended periods may be very detrimental and may ultimately cause the tool to become inoperative.

One object of my invention, therefore, is to permit the hydraulic mechanism to be operated in any position without danger of air getting into the hydraulic system.

Another object of my invention is to eliminate the so-called follow-up piston and packings.

Still another object of my invention is to provide an easy means of access to the hydraulic system so that fluid may be readily introduced therein without danger of air getting into the system.

A further object of my invention is to provide all the foregoing advantages at low cost since it does not require the extremely careful polishing and close tolerances that a cylindrical reservoir and follow-up piston require.

Another object is to eliminate friction and wear of moving parts, which ultimately may cause replacement of packings, refinishing of cylinder walls, etc.

I accomplish these and other objects and obtain my new results as will be apparent from

the device described in the following specification, particularly pointed out in the attached claims, and illustrated in the accompanying drawing, in which:

5 Fig. 1 illustrates a side view of a form of hydraulic press.

Fig. 2 illustrates a sectional view of the reservoir or receptacle made of a rubber compound.

Fig. 3 illustrates a sectional view of the reservoir or receptacle having contracting metal walls.

Referring more particularly to the drawing, reference numeral 10 designates a portable press, illustrated in Fig. 1, with integral handle 11, pivoted lever 12, body 13, and a head 14, all shown in cross section in co-pending application Ser. No. 224,820.

Threadedly engaging the body 13 is the reservoir cap 15 within which is contained, as shown 20 in Fig. 2, a flexible container, receptacle or sack 16, made of resilient material preferably a rubber-like compound that can withstand oil, such as neoprene.

At the mouth of the sack, adjacent the orifices 25 17 and 18, a metal ring 19 is preferably molded integrally therewith. Thus the rim 20 of the molded material which covers the inner and contact face of the ring, acts as a gasket when the sack is clamped to the body 13 by rotating the 30 reservoir cap 15 thereon.

The other end of the sack 16, is molded into a tubular section 21, with metal spout 22 integrally bonded or otherwise attached thereto, to form a sealed joint. This spout is used to fill the 35 sack with hydraulic fluid and is capped by a closure 23. The spout may be provided with flat external side walls 24, for use with a wrench to insure a tight fit between spout and closure.

The integral handle 11 is provided with threaded section 25, which engages an internally threaded section 26 of the reservoir cap 15.

As the handle 12 is oscillated towards handle 11 in a scissors-like action, a piston, not shown, pumps the fluid from the sack 16 into the pressure chamber not shown, through orifice 17. If the overload is reached, or the release valve of the press is actuated, as described in the co-pending application Ser. No. 224,820, the fluid is returned to the reservoir 16 through orifice 18.

The follow-up effect of the piston previously used in the reservoir is thus obtained by the use of the collapsible rubber sack, preventing air from entering the hydraulic system. A similar effect may be obtained by the use of the

flexible metal bellows 30, shown in Fig. 3. Here the ring 31 is attached to the rim 32 of the bellows, and the reservoir cap 15 seals the bellows to the body 13, preventing leakage.

The remaining end of the bellows is formed into a tubular section 33, terminating in a closure 34.

As the oil is pumped from the bellows 30, the external air pressure causes the bellows to contract to take up the loss in volume, and at the same time prevents the air from entering the oil chamber.

If sufficient air does not leak in through the threaded section of the handle 11, a small aperture 35, may be provided, to permit the atmospheric pressure to operate the collapsible oil reservoir inside the reservoir cap 15.

In the operation of my invention, using a neoprene sack, I have caused the sack to be collapsed and refilled more than 5000 times without any sign of wear or deterioration.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

What I claim and desire to secure by Letters Patent, is as follows:

1. A container for attachment to a supporting structure having an orifice therein, comprising a rigid outer wall with an opening at one end thereof, and means for rigid attachment of the outer wall to the supporting structure with the orifice and the opening in communication, said outer wall provided with an aperture at the remaining end thereof; and an inner collapsible chamber provided with an opening at one end thereof in communication with the orifice of the supporting structure, the other end of said chamber having an aperture and closure therefor in communication with the aperture in the outer wall, that portion of the chamber containing the aperture and closure therefor being freely

movable within the rigid outer wall whereby the chamber may be completely collapsed within the rigid outer wall under atmospheric pressure.

2. A container for attachment to a supporting structure having an orifice therein, comprising a rigid outer wall with an opening at one end thereof, and means for rigid threaded attachment of the outer wall to the supporting structure with the orifice and the opening in communication, said outer wall provided with an aperture at the remaining end thereof; and an inner collapsible chamber provided with an opening at one end thereof in communication with the orifice of the supporting structure, said collapsible chamber being made of rubber, and having a metal ring bonded to said chamber about the opening thereof to permit the outer wall to compress the bonded metal ring to the supporting structure when the outer wall is threaded thereto, the other end of said chamber having an aperture and closure therefor in communication with the aperture in the outer wall, that portion of the chamber containing the aperture and closure therefor being freely movable within the rigid outer wall whereby the chamber may be completely collapsed within the rigid outer wall under atmospheric pressure.

3. A container for attachment to a supporting structure having an orifice therein, comprising a rigid outer wall with an opening at one end thereof, and means for rigid attachment of the outer wall to the supporting structure with the orifice and the opening in communication, said outer wall provided with an aperture at the remaining end thereof; and an inner collapsible chamber provided with an opening at one end thereof in communication with the orifice of the supporting structure, the other end of said chamber having an aperture and closure therefor in communication with the aperture in the outer wall, the aperture in the outer wall, the aperture in the outer wall being provided with an extending hollow closure within which the closure for the aperture of the flexible chamber is freely movable, and providing access to the closure for the flexible chamber upon removal of the extending closure of the outer wall, that portion of the chamber containing the aperture and closure therefor being freely movable within the rigid outer wall and closure therefor whereby the chamber may be completely collapsed within the rigid outer wall under atmospheric pressure.

MARVIN LEE.
